UNITED STATES PATENT OFFICE.

JOHANNAH V. DOUGHERTY, OF DETROIT, MICHIGAN.

BEDSTEAD.

No. 815,077.

Specification of Letters Patent.

Patented March 13, 1906.

Application filed March 8, 1905. Serial No. 248,974.

To all whom it may concern:

Be it known that I, JOHANNAH V. DOUGHERTY, a citizen of the United States, residing at Detroit, in the county of Wayne, State of Michigan, have invented certain new and useful Improvements in Bedsteads; and I do hereby declare the following to be a full, clear, and exact description of the invention, such as will enable others skilled in the art to 10 to which it appertains to make and use the same.

This invention relates to bedsteads and mattresses therefor, the object of the invention being to provide a cheap and simple construction of bedstead which may be readily 15 adjusted to form a single or a double bed.

A further object of the invention is to provide a particular form of mattress which may be used upon the double bed as a spring-mattress or by folding may be used upon the single bed either as a spring-mattress or as a 20 stuffed mattress.

In the drawings forming a portion of this specification, and in which like numerals of reference indicate similar parts in the several 25 views, Figure 1 is a top plan view showing a bedstead embodying the present invention. Fig. 2 is a section on line 2 2 of Fig. 1. Fig. 3 is a detail elevation of one end portion of the middle rail of the bedstead. Fig. 4 is a transverse section through the mattress in its unfolded position. Fig. 5 is a view similar to 30 Fig. 4, showing the mattress in its folded position.

Referring now to the drawings, the present 35 bedstead comprises a main frame including rails 10 and 11, which are rigidly connected at their ends in parallel relation by the end pieces 12 and 13, there being thus formed a rectangular frame, and this frame is provided with supporting-legs 14 at its corners. In connection with this main frame there is 40 employed a supplemental frame including a rail 15, having supporting-legs 16 and 17 at its ends, to which are also connected end pieces. These end pieces comprise each 45 vertically-spaced rods 18 and 19, of which the upper rod is extended beyond the lower rod and around the rail 11 of the main frame and then rearwardly beneath and in close relation 50 to the lower rod 19, the rail 11 having a depending portion 20 at each end which receives the corresponding rod 18 slidably. The rail 15 may be moved toward and away from the main frame, and by pressing the rods 19 upwardly the portions 20 of the rail 11 may be 55 passed between the ends of the rods 18 and

19 to disengage the main and supplemental frames. The legs at the ends of the rails 10 and 15 are continued above the rails to form posts 21 and 22, respectively, which posts at 60 each end of the bedstead are connected by a lazy-tongs arrangement of slats 23 and 24, the slats 24, that are connected at the upper ends of the posts, being attached or pivoted directly to rings 25, that slidably engage the 65 posts for vertical movement thereon. With this construction it will be understood that the bedstead may be adjusted as to width to form a single or a double bed.

In connection with the bedstead there is 70 employed a mattress comprising two rectangular frames 30 and 31, connected, by means of hinges 32, at one edge. The frame 30 is provided with a spring fabric 34 at each side, while the frame 31 is provided with a spring 75 fabric 35 at one side and a stuffed tick 36 at its opposite side. The frame 30 is somewhat thicker than the frame 31, so that when the frames are in the position shown in Fig. 4 the woven fabric of the frame 31 will be in the 80 same plane with the woven fabric or spring fabric of the frame 30 for use on the double bedstead. When the two frames are folded together, they may be disposed with either the tick of one frame or a spring fabric of the 85 other frame uppermost, as may be preferred.

What is claimed is—

1. A bedstead comprising a main frame including rails and connected end pieces and supporting-legs, one of the rails having depending portions at its ends, and a supplemental frame comprising a rail, end pieces and supporting-legs, the end pieces of the supplemental frame comprising vertically-spaced rods, the uppermost rod of each end 95 piece being slidably engaged in a depending portion of the main frame and returned therebelow beneath the lower rod.

2. A bedstead comprising a frame including rails and connected end pieces and supporting-legs, a supplemental frame comprising a rail, end pieces and supporting-legs, the end pieces of the supplemental frame comprising spaced rods, the uppermost rod of each end piece being slidably engaged with a 105 portion of the main frame and turned therebelow beneath the lower rod the said lower rod being movably engaged with the said upper rod to permit of detachment of one frame with respect to the other.

3. A bedstead comprising a main frame including rails and connected end pieces and

supporting-legs, one of the rails having depending portions at its ends, and a supplemental frame comprising a rail, end pieces and supporting-legs, the end pieces of the supplemental frame comprising vertically-spaced rods, the uppermost rod of each end piece being slidably engaged in the depending portion of the main frame and returned therebelow beneath the lower rod, and lazy-tongs connecting those portions of the legs above the rails at each end, the said tongs including members slidably connected with said legs.

4. A bedstead comprising a frame including rails and connected end pieces and supporting-legs, a supplemental frame comprising a rail, end pieces and supporting-legs, the end pieces of the supplemental frame com-

prising spaced rods, the uppermost rod of each end piece being slidably engaged with a portion of the main frame and turned therebelow beneath the lower rod the said lower rod being movably engaged with the upper rod to permit of detachment of one frame with respect to the other, and lazy-tongs connecting those portions of the rails above the rails at each end, said tongs including members slidably connected with said legs.

In testimony whereof I affix my signature in presence of two witnesses.

JOHANNAH V. DOUGHERTY.
